UNITED STATES PATENT OFFICE.

CHARLES B. MORROW, OF CHICAGO, ILLINOIS.

DESIGN FOR A PEDESTAL DISPLAY-RACK.

SPECIFICATION forming part of Design No. 30,771, dated May 16, 1899.

Application filed February 10, 1899. Serial No. 705,217. Term of patent 3½ years.

To all whom it may concern:

Be it known that I, CHARLES B. MORROW, a citizen of the United States, residing at Chicago, in the county of Cook and State of Illinois, have invented and produced a new and useful Design for Pedestal Display-Racks for Fabrics and Like Articles, of which the following is a specification, reference being had to the accompanying drawing.

10 The figure of the drawing is a perspective view of the pedestal display-rack embodying my design.

The leading feature of my design consists in a standard A, mounted upon a suitable base B and provided with a number of sets

of arms C C, arranged in tiers above one another. The arms C C extend upwardly and a little downwardly from their points of connection with the standard A, thence outwardly, and thence downwardly. Their outer 20 ends are bent again outwardly and upwardly, so as to form a small hook e.

Having thus described my invention, what I claim is—

The design for a pedestal-rack for fabrics 25 or like articles, as herein shown and described.

CHARLES B. MORROW.
